UNITED STATES PATENT OFFICE.

FRANK W. HENRIKSON, OF MULBERRY, KANSAS.

FLYING SWITCH.

1,424,198.

Specification of Letters Patent. Patented Aug. 1, 1922.

Application filed September 13, 1921. Serial No. 500,386.

To all whom it may concern:

Be it known that I, FRANK W. HENRIKSON, a citizen of the United States, residing at Mulberry, in the county of Crawford, 5 State of Kansas, have invented certain new and useful Improvements in Flying Switches, of which the following is a description, reference being had to the accompanying drawing and to the figures of 10 reference marked thereon.

This invention relates to railway switches, and more particularly to a flying switch especially adapted for mine use.

At the present time when a dinkey or 15 motor hauling a train of mine cars is approaching a siding, at which point it is desired to shunt the dinkey onto the siding and to send the cars down the main track, the operator on the dinkey pulls the coupling pin when about thirty feet from the 20 siding switch thereby uncoupling the dinkey from the train of cars. The dinkey then speeds up and pulls away from the following cars so that about thirty feet intervenes.

25 The spring switch has been previously set for the dinkey to pass into the siding. After the dinkey has passed over the switch into the siding, the engineer on the dinkey reaches out from the side of the dinkey and

30 manually throws a lever upstanding by the side of the track to throw the spring switch to main track position so that the oncoming train of mine cars is directed straight down the main track and not on the siding. On

35 the return trip when the dinkey is returning with a load of empties before the dinkey reaches the switch, the engineer on the dinkey reaches out and throws the switch back to the siding position so that the dinkey

40 and empties can pass up along the main track in the reverse direction. At the other end of the main track the reverse operation of the corresponding siding switch takes place, i. e., at the point it is desired to shunt

45 the empties onto the siding and to pass the dinkey up the main track to couple to more loaded cars. Accordingly when the dinkey with a load of empties arrives at a point about thirty feet in advance of the switch,

50 the dinkey is again uncoupled from the empties as before. This switch is already set for straight ahead so that the dinkey proceeds along the straight track. The operator on the leading mine car reaches

55 out and throws the upstanding lever at the side of the track to throw the switch so that

the cars do not go up the main track but pass onto the siding. In order to reset the switch for next time, the operator must then drop off the moving mine cars which have 60 passed onto the siding, go back to the switch and reset it for the straight track position.

All of these operations require the presence of an extra operator on the mine cars, and in some types of switches,—separate operators must be stationed on the ground at the 65 switches to throw them at the proper time. The manual operation of these switches is objectionable because if the operator does not throw the switch at the proper moment, 70 much time is lost in re-routing the cars and accidents are liable to result. Furthermore, experience has shown that the practice of having an operator jump off a moving train 75 of cars to reset the switch is most dangerous and has resulted in many accidents.

One of the objects of the present invention is to provide a switch which is automatically operated by the moving dinkey when approaching the switch from one direction to throw the switch one way, and when approaching the switch from the other direction, to throw the switch the other way.

Another object of this invention is to provide such a double-acting flying switch which can be thrown independently of the automatic mechanism by the action of the wheels of a car crowding the switch over to desired position, just as an ordinary type 85 of spring switch operator.

Still another object of this invention resides in providing a double-acting flying switch which can be also manually operated to throw it in either direction.

95 A further feature of this invention resides in providing manual means for throwing the switch in either direction with means whereby the switch can be locked in such positions so as to preclude either manual or automatic operation thereof.

Another feature resides in providing means whereby the switch can be locked against manual operation while permitting its free automatic operation as a flying 105 switch.

Still another object resides in the novel construction of the throwing block which is depressed by the contact of the dinkey or wheels approaching it from either direction and which causes the operation of the 110 switch first in one direction or the other cor-

responding to the direction of approach of the dinkey or other operating vehicle.

A further feature of this invention resides in the novel construction of the throwing block and its manner of cooperation with the three reverse-block throwing cranks whereby the main or central crank is given a preliminary throw by either of the leading cranks on opposite sides thereof, from a vertical dead center position to a position inclined in the direction of throw of such central crank either to the right or left according to the direction of approach of the actuating vehicle or dinkey.

Another feature of this invention resides in the provision of rollers which cooperate with the inclined surfaces on either end of the jointed throwing block whereby to insure the movement of the throwing block in the same direction as the preliminary setting of the main or central crank which has been inclined in the proper direction by the selected leading crank.

Yet another object of the invention resides in the novel arrangement of the two leading cranks and the intermediate reversing crank in which the two leading cranks are normally held by spring tension in a position inclined toward the normally vertically positioned intermediate crank.

Still another object of this invention resides in forming the throwing block of two pivoted sections, the central position of the block having a bearing for actuating the main crank, and the ends of the block having elongated slots to receive the leading cranks, each elongated slot permitting free movement of its leading crank therein after such leading crank has given the block the preliminary shifting movement to throw the main crank off dead center.

A further object of this invention resides in providing double-acting spring operated means for holding the switch in thrown position, which means permits the free shifting of the switch by the crowding of the wheels thereagainst.

A further object resides in providing the switch stand with a shiftable indicator, either a light or a sign, which shows the position of the switch to the operator of the approaching train.

Another feature of the invention consists in forming the reversing block with a recessed yoke whose internal faces are inclined inwardly and downwardly so that minimum length of crank will produce a maximum throw of the reversing block in either direction.

These and other objects will in part appear obvious and will in part appear apparent from a perusal of the accompanying specification when taken in connection with the accompanying drawings, in which—

Figure 1 is a plan view of the switch

shown in operation with the siding track;

Fig. 2 is a sectional view of the reverse block on the line 2—2 of Fig. 1;

Fig. 3 is a section on the line 3—3 of Fig. 2;

Fig. 4 is a side elevation of the throwing block for throwing the reverse block on the line 4—4 of Fig. 1;

Figures 5 and 6 are views of various positions of the throwing block;

Fig. 7 is a side section of the throwing block, the cranks and the reverse block on the line 7—7 of Fig. 1;

Fig. 8 is a fragmentary view of the reverse block in another position;

Fig. 9 is a section on the line 9—9 of Fig. 1;

Fig. 10 is an additional view of the switch and track shown in Fig. 1, but with the switch in its thrown position, and

Fig. 11 is a section on the line 11—11 of Fig. 1.

Referring now to the drawings in detail, the main track 1 is provided at the desired point with the siding track 2 and with the shiftable switch points 3 for either shunting the cars to the siding or directing them straight down the main track as will be hereinafter made manifest. Under certain circumstances, these switch points can be

operated as ordinary spring switches. They are pivoted at 4 and are shifted laterally by means of the sliding bar 5 operated by the link 6. This link is pivotally connected as at 7 to the block 8 which is in turn pivotally mounted on a pin 9 to the switch stand 10. This pivotal pin 9 extends upwardly through a supporting bracket 10' and is provided with a signal 10'' such as

the usual lights on an indicator. In order to retain the switch in any thrown position, the block is provided at 11 with a pivotal connection to a lever 12, the free end of which passes through an opening in an upstanding ear 14 on a bracket 15 mounted

on the stand 10. A spring 16 is coiled between the inner end of lever 12 and the ear 14 so that when the block is thrown to one or the other side of a straight line between the pivot 9 and the ear 14, it will be fur-

ther thrown by the spring and will be retained in such position. This spring as thus arranged also permits the switch to be thrown by being crowded by the car wheels.

At a desired distance from the pivotal point 4 of the switch points, in the present instance, a distance equal to the length of the dinkey, although in some cases it may be the standard mine car train length which is thirty cars plus the length of the dinkey,

there is located the mechanism for automatically throwing the switch by contact with the moving vehicle, such as by the wheels of the dinkey.

As shown clearly in Figures 1 and 7, this

mechanism comprises a base or standard 18 located adjacent the rail 2 of the siding, and preferably formed with spaced upstanding bearings 19 and 20 arranged in pairs, there being three pairs. These bearings support the oscillatable cranks 21, 22 and 23. These cranks are provided at one end with rather short crank arms 26, 25 and 24, respectively, which in turn are formed with circular studs 27, 28 and 29, respectively. The outer cranks 21 and 23 terminate at their opposite ends at their bearings 20 whereas the middle crank 22 is longer and is provided with a relatively long crank arm 30 formed with a circular stud 31, which carries a friction roller 32. Coiled about each of the cranks 21, 22 and 23 are the springs 33, 34 and 35, each of which has one end fast to a collar 36 on the particular crank, the other end of the spring being fast to the bearing member 20. As illustrated in Fig. 4, these springs are normally arranged so that the two outside cranks 24 and 26 are inclined inwardly toward the intermediate crank 25 while the central spring 34 maintains the crank 28 in a natural vertical position. This is an important feature.

These cranks 24, 25 and 26 are adapted to operatively connect with the throwing block. The throwing block is preferably made of two sections 37 and 38 jointed or dove-tailed together at the center as at 39 (see Figures 1 and 7) so that one section can be depressed in advance of the other.

Each of the sections 37 and 38 is provided with an elongated slot 40 and 41, respectively, and are formed at their junction 39 with a circular aperture. The slots 40 and 41 receive the pins or lugs 27 and 29, respectively, while the circular aperture receives the intermediate crank pin 28. The outside under surface of each section is beveled upwardly as at 42 and 43 to constitute an inclined or cam surface to operate with friction rollers 46 and 45 disposed beneath the ends of the sections and journaled to the base or standard 18. Figures 5 and 6 give a clear idea of the action of the cam face 43 on the roller 46.

The reverse block is mounted in the standard or base 18 to the rear of the throwing block and cranks. It comprises a yoke 46' see Fig. 2 provided with oppositely extending arms 47 and 48 which slide in upright bearings 49 and 50 secured to the base. These uprights are provided with friction rollers 51 and 52 which rotate in a horizontal plane and thus insure the free sliding movement of the reverse block.

The base is likewise provided with an upright support 53, (see Fig. 3) provided with spaced friction rolls 54 and 55 which rotate about vertical axes and receive between them the free end of the arm 47.

This bearing prevents lateral movement of 65 the reverse block.

The inner contour of the yoke-shaped portion 46' of the reversing block comprises the inwardly and downwardly inclined cam faces 56 and 57 which are designed to cooperate 70 with the friction roller 32 on the pin 31 of crank 30 so that when the crank is oscillated to the right or to the left the reverse block will be shifted accordingly. By inclining these faces 56 and 57, the maximum 75 throw of the block is secured with minimum length of crank arm 30. At its upper portion, the yoke is arcuately cut away as at 58 and 59 to permit this movement.

The free end of arm 47 is pivotally connected to a lever 60 in turn pivotally connected at 61 to block 8.

In order to permit a hand operation of the reverse block 46, in case the automatic mechanism be out of operation, the crank pin 31 85 see Fig. 7 of the longer crank arm 30 is provided with an integral projection 62, preferably formed rectangular or angular to key thereto a vertically depending arm 63 provided at its base with spaced ears 64 90 between which are pivoted the hand lever 65. This lever is formed with a slot 66 so that when the lever is swung to vertical position in the plane of the arm 63, the end of the rectangular projection 62 will pass 95 through the similarly formed slot so that the lever will be rigid with the arm 63 for throwing the reverse block to the right or to the left.

The base 18 is additionally provided with 100 upright ears 67, 68 and 69. The ear 67 is located to the extreme left of the reverse block in such a position that when the lever 65 is thrown to its limit in that direction, the lever will pass behind the ear and can 105 be locked by a cross pin 70. Reversely, when the lever 65 is thrown to extreme opposite position, it will be behind the ear 69 and can be locked by pin 71. Both of these positions prevent either the manual or automatic operation of the switch.

The ears 68 are disposed in the plane of the crank 22 so that when the arm 65 is swung down to a horizontal position, as in Fig. 1, it will lie between these ears and can 115 be locked by pin 72'. In this position the switch is free to be operated automatically but not manually, since the arm 65 is formed with the round extension 72 which is free to oscillate between the ears 68 as the crank 22 120 is oscillated.

Operation.

In the operation of the device, when a dinkey and train of mine cars are approaching the switch from the left-hand end of Fig. 1, when the dinkey arrives about thirty feet from the switch, the dinkey is uncou-

pled from the mine cars, the engineer speeds up so that the dinkey runs ahead of the on-coming cars. The switch points are already set for the siding so that the dinkey 5 passes onto the track 2. After the last wheels of the dinkey leave the switch point at the pivot 4, the front wheels of the dinkey, or any predetermined part of the dinkey, strike the throwing block, which is normally 10 in the position illustrated in Fig. 4. As the wheel passes onto the section 37 it is depressed to the position shown in Fig. 5, the crank 21 being oscillated inwardly and the pin 27 sliding in the elongated slot 40 of 15 the section 37. This sinking movement of the sector 37 oscillates the central crank 25 from a pure vertical position to a position inclined in the direction in which the dinkey is moving, toward the right in Fig. 5. This 20 is the preliminary setting movement to insure that the central crank 25 does not remain in vertical position preparatory to the wheel passing entirely across sections 37 and 38. It will be observed that the inclined 25 under surface 43 of the section 37 is now resting on the friction roller 46, which construction additionally insures the movement of the section 37 to the right in Fig. 5. The dinkey wheel is now passing across the junction 30 of the sections 37 and 38 of the throwing block and in doing so, depresses the same to the position shown in Fig. 6. This movement completely oscillates the intermediate crank 25 by reason of the pin 28 35 in the aperture in the joined sections, and this oscillation of crank 22 is transmitted to crank arm 30 to swing the reversing block to its extreme lateral position, the roller 32 wiping down the inwardly and downwardly 40 inclined cam face 57. This shifting of the reversing block through the lever 60 swings the block 8 about its pivot 9, and when the block has moved over the straight line between the pivot 9 and the lever 12, the coiled 45 spring 16 will snap the switch points 4 back to the main track position so that the on-coming mine cars will pass down the main track and will not follow the dinkey. Obviously, after the wheel has passed off the 50 sections 37 and 38, they will be instantly returned to upright position by means of the coiled springs 33, 34 and 35.

Now when the dinkey returns up the siding 2 with a load of mine cars, the dinkey 55 will approach the throwing block from the opposite direction and the operation of the sections 38 and 37 will be just the reverse. In this instance, the section 38 will be the active section to accomplish the preliminary 60 throw or oscillation of the central crank 25. The section 37 in this case will be the idle section, the crank pin 27 will shift idly in the slot 40 just as did the crank pin 29 shift idly in the slot 41 when the section 37 was

the initially active section to perform the 65 preliminary throwing of the intermediate crank 25, as first described. As the wheels of the dinkey pass onto the junction of the two sections 37 and 38 from the last described direction, the switch points through 70 the intermediate mechanism will be thrown from the main track to the siding position so that the dinkey and cars can pass up the main track in the reverse direction or from the right-hand to the left-hand side of 75 Fig. 1.

It will be obvious that the switch points 3 are free to be crowded over by the action of the wheels, just as any ordinary spring switch will be operated, this free operation 80 not being interfered with by the automatic features of the switch.

It is obvious that minor changes may be made in the construction illustrated, it not being intended to limit the invention to the 85 exact details shown and described except as the disclosure is limited by the scope of the appended claims.

Having thus described the invention, what I claim as new and desire to secure by Letters-Patent, is:—

1. In a device of the class described, in combination with a main track and its siding, a pair of switch points adapted to be shifted into either position, means comprising a single throwing block connected to said switch points and arranged adjacent said siding adapted to be depressed by a vehicle moving along said siding, said block being constructed and arranged to automatically throw said switch points in one direction when depressed by a vehicle approaching from one direction and to automatically throw the switch points reversely when depressed by a vehicle approaching from the 105 opposite direction.

2. In a device of the class described, in combination with a main track and siding, a pair of switch points adapted to be shifted into either position, automatic means arranged adjacent said siding and connected to said switch points and adapted to be depressed by a vehicle moving along said siding, said means being constructed and arranged to automatically throw said switch points in one direction when depressed by a vehicle approaching from one direction and to automatically throw the switch points reversely when depressed by a vehicle approaching from the opposite direction, said 110 means permitting the free lateral crowding of the switch points by the wheels of the vehicle.

3. In a device of the class described, in combination with a main track and siding, a 115 pair of switch points adapted to be shifted into either position, automatic means arranged adjacent said siding beyond the piv-

total point of said switch points and connected to said switch points adapted to be depressed by a vehicle moving along said siding, said means being constructed and arranged to automatically throw said switch points in one direction when depressed by a vehicle approaching from one direction and to automatically throw the switch points reversely when depressed by a vehicle approaching from the opposite direction, and manually operable means connected to said mechanism for throwing said switch points in either direction.

4. In a device of the class described, in combination with a main track and siding, a pair of switch points adapted to be shifted into either position, automatic means arranged adjacent said siding and connected to said switch points and adapted to be depressed by a vehicle moving along said siding, said means being constructed and arranged to automatically throw said switch points in one direction when depressed by a vehicle approaching from said direction and to automatically throw the switch points reversely when depressed by a vehicle approaching from the opposite direction, manually operable means connected to said mechanism for throwing said switch points in either direction, and means for locking said manual means against manual operation while permitting the free operation of said automatic means.

5. In combination with a siding switch, a throwing block arranged adjacent the siding track and adapted to be depressed by the moving vehicle, said block comprising two pivotally connected sections, an intermediate crank having a pin pivotally connected to the junction of said sections, two exterior cranks, each having a pin making a swinging connection in an elongated slot in the outer end of each section, means for normally maintaining said intermediate crank in vertical position and for normally maintaining said exterior cranks inclined inwardly toward said intermediate crank, and means for shifting said switch in one direction or the other on the oscillation of said intermediate crank in one direction or the other.

6. In combination with a siding switch, a throwing block arranged adjacent the siding track and adapted to be depressed by the moving vehicle, said block comprising two pivotally connected sections, an intermediate crank having a pin pivotally connected to the junction of said sections, two exterior cranks, each having a pin making a swinging connection in an elongated slot in the outer end of each section, means for normally maintaining said intermediate crank in vertical position and for normally maintaining said exterior cranks inclined inwardly toward said intermediate crank, 65 means for shifting said switch in one direction or the other on the oscillation of said intermediate crank in one direction or the other, and means for insuring the initial oscillation of either outside crank toward the central crank to thereby give said latter crank a movement away from the vertical.

7. In combination with a siding switch, a central crank adapted to be depressed by a moving vehicle and to throw a switch in one direction or the other according to its direction of depression, means connecting said crank with said switch, means for normally maintaining said crank in substantially vertical position, and means for preliminarily swinging said central crank from said vertical position into a position inclined in the direction in which it is to be depressed.

8. In combination with a siding switch, a central crank adapted to be depressed by a moving vehicle and to throw a switch in one direction or the other according to its direction of depression, means connecting said crank with said switch, means for normally maintaining said crank in substantially vertical position, a crank arranged on each side of said central crank adapted to be depressed by and in the direction of movement of the vehicle, and means operable by the depression of either of said cranks for preliminarily swinging said central crank from said vertical position into a position inclined in the direction of the moving vehicle.

9. In combination with a siding switch, a throwing block arranged adjacent the siding track and adapted to be depressed by the moving vehicle, said block comprising pivotally joined sections constructed and arranged to be sequentially depressed in one direction or the other corresponding to the direction of approach of the moving vehicle, and means connecting said block to the switch point to automatically throw said switch in one direction or the other according to the order of sequential operation of said sections.

10. In combination with a siding switch, a crank adapted to be thrown in one direction or the other by a moving vehicle depending upon its direction of approach, a second crank arm fixed to said crank and oscillating with it, a yoke having downwardly and inwardly inclined sides arranged on opposite sides of the center of oscillation of said second crank arm and adapted to be wiped thereby to shift said yoke laterally, and a connection between said yoke and said switch to operate the same.

In testimony whereof, I affix my signature.

FRANK W. HENRIKSON.
